UNITED STATES PATENT OFFICE.

FOKKO H. G. BRANDT, OF KANSAS CITY, KANSAS, AND GEORGE K. KRELL, OF KANSAS CITY, MISSOURI.

KNOCKDOWN SCAFFOLD.

Application filed November 8, 1920. Serial No. 422,747.

To all whom it may concern:

Be it known that we, FOKKO H. G. BRANDT and GEORGE K. KRELL, citizens of Germany, and residents, respectively, of Kansas City, 5 county of Wyandotte, State of Kansas, and Kansas City, county of Jackson, State of Missouri, have invented a certain new and useful Improvement in Knockdown Scaffolds, of which the following is a complete 10 specification.

This invention relates to knockdown scaffolds for use in the erection or interior decoration or redecoration of buildings, and our object is to produce a scaffold which can be 15 erected or knocked down with unskilled labor and in less time and with less danger to those engaged in erecting or dismantling the scaffold than with the usual type of scaffold.

20 Another object is to produce a scaffold adapted for use at any desired height, which may be increased in height as the walls of a building being erected necessitate such increase in the height of the scaffold, and 25 from which when built to a predetermined height, the flooring may be removed and carried to another level to accommodate increase in the height of the walls of the building.

30 Another object is to produce a scaffold in which the parts are held together by clamping action and which embodies the desirable features of simplicity, strength, durability and cheapness in the assembling and 35 dismantling operations, and a scaffold which may be used repeatedly without material deterioration.

With these general objects in view and others, as hereinafter appear, the invention 40 consists in certain novel and peculiar features of construction and combinations of parts, as hereinafter described and claimed, and in order that it may be fully understood reference is to be had to the accompanying 45 drawings, in which—

Figure 1 is a fragmentary side elevation of a building wall and a scaffold embodying the invention.

Figure 2, is a horizontal section of the 50 same.

Figure 3, is an enlarged central vertical section of one of the standards or uprights forming a part of the scaffold.

Figure 4 is a section on the line IV—IV 55 of Figure 3.

Figure 5 is a section on the line V—V of Figure 3.

Figure 6, is a side elevation of an adjustable connection between one of the standards or uprights of the scaffold and the walls of 60 the building being erected.

Figure 7, is a top view of the same.

Figure 8, is a fragmentary side view showing the means for securing one of the longitudinal stringers or one of the cross-ties of the scaffold to one of the standards or 65 uprights.

Figure 9, is a plan view of the same.

Figure 10, is a side elevation showing the means whereby one of the standards or uprights of an interior scaffold is braced 70 against the wall of the building at the point where no opening occurs in said wall.

Figure 11, is a top view of the construction shown by Figure 10. 75

Referring first to the scaffold generally and secondly to details of the same, 1 indicates the wall of a building shown in Figures 1 and 2 as in course of erection, 2 a window opening in the building, and arranged at suitable distances outward of the walls of the building and spaced equal distances apart, are an inner series of standards or uprights 3 and an outer series of standards or uprights 4. The standards or uprights 80 85 3 and 4 of each series are connected by longitudinal stringers 5 which are preferably of sufficient length to span the space between more than two of the standards or uprights. Similar longitudinal stringers 5 connect the standards or uprights 3 and 4 at the other sides of the building and occupy a plane approximately a foot or thereabouts higher than those of the first-named series of stringers, it being noted by reference to sheet 1 that only one set of each series of uprights and stringers is shown and that the extremities of one set of stringers overlie the extremities of the other set extending in a 90 different direction at the corner of the building.

Extending transversely across the parallel stringers of each set of stringers and against the inner and outer standards or uprights are cross ties 6, and laid upon the cross ties of each series and extending 100 105 parallel with the respective stringers are flooring boards or planks 7 upon which the workmen may safely stand and move about in the course of their employment.

In the erection of the scaffold, it is de- 110

sirable that some of the standards or uprights shall be disposed outward of window openings, one vertical series of which is shown, and opposite some of the window openings ties or anchors 8 will be secured to the adjacent uprights and extend therefrom through said window openings and be equipped with clamping levers 9 for engagement with the building wall at the inner and outer sides thereof. A comparatively few of these ties or anchors will lend stability and rigidity to the scaffold by tending to maintain the uprights in parallel relation with the walls of the building.

13 A set of stringers and cross ties will be arranged in superposed relation and preferably spaced five or six feet apart, though the distance between one set of stringers and cross ties and the set above the same may 20 of course be varied.

14 A building can be erected with only one set of flooring boards for each side of the building, though additional sets may be employed if desired. If only one set is employed, the workmen after building the wall to a suitable height beyond the flooring, can then remove the latter and place it upon the next set of cross ties above, these actions being repeated as the height of the walls 30 increase and of course reversed in removing the scaffold, that is the flooring is lowered from one series of cross ties to another in effecting the dismantling of the scaffold.

15 Where a scaffold is erected in a large room or auditorium to enable the same to be decorated or redecorated, it may be possible occasionally to run the ties or anchors 8 out through the window openings and secure the scaffold to the wall in a manner similar 40 to that described. If this is impracticable due to the character of the walls of the room or auditorium, brace rods 10 secured at one end to selected standards or uprights, will extend outward therefrom and be equipped 45 at their outer ends with shoes 11 to bear against the adjacent walls.

16 Referring now to details of the scaffold and first to sheet 2 of the drawings, it will be seen that each standard 3 and 4 comprises a plurality of superposed members 12, of gradually diminishing diameter by preference, as shown clearly by Figure 3, each member being diametrically reduced near its upper end at 13 to provide external 50 shoulders 14 and 15 and a socket 16 at its upper extremity wherein is fitted the lower end of the superposed member, this arrangement permitting of the use of members of different diameter, the bottom member being 55 of greatest diameter and the topmost member of smallest diameter. This arrangement is advantageous not only because it apportions the strain scientifically and diminishes the weight of the scaffold as a whole, but 60 also because it relieves the operators of labor 65

and facilitates the erection or dismantling of the scaffold by the use of lighter standard members as the scaffold increases in height. Each standard member 12 is reduced in diameter near its lower end to form a neck 17 and external shoulders 18 and 19 and the lower end of the bottom member rests on a base 20 and within a socket 21 thereof and the upper end of said base is provided with an external groove 22. The base may be 75 securely fastened to the ground in any suitable manner but preferably will be provided with a broad foot plate 23 and radiating ribs 24 to stiffen and strengthen it.

17 To reliably secure the lower member 12 to the base, a collar clamp is employed, the same comprising two similar members 25 terminating at opposite ends in outwardly projecting ears 26 secured together by clamping bolts 27 and nuts 28 or equivalent retaining devices. The upper halves of the collar members are of the proper diameter to tightly embrace the neck 17 of said member 12 between the shoulders 18 and 19 thereof, and the internal diameter of the lower halves of the collar members is enlarged at 29 to receive the upper end of the base 20 and there are provided internal ribs 30 to fit in the external grooves 22 of the base. This construction and arrangement make it impossible for the said member 12 to move downwardly or upwardly.

18 Each member of a standard telescopes a short distance into the member immediately below it and the members so engaging are secured firmly together by a clamp consisting of a pair of collar members 31 terminating in ears 32 secured together by bolts 33 and nuts 34 or equivalent devices, said collars fitting snugly around the enlarged upper end of one of said standard members and being diametrically reduced below said enlargement to fit snugly around the reduced or neck portion 13 and against the shoulders 14 and 15 of said member.

19 The upper ends of the collar members are reduced to fit snugly around the neck portion 17 and between the shoulders 18 and 19 of the other member 12, and in this connection it should be stated that the members 31 for the entire scaffold will preferably be of the same size, but of such resiliency that the pull of the fastening bolts and nuts shall adapt or bend the said collar members sufficiently to perform their function regardless, 115 within reasonable limits, of the diameter of the standard to which they are fitted. By thus making the collars of a single size the cost of the scaffold as a whole is reduced and there will be no necessity for selecting particular collar clamps to fit particular standards, which of course would delay the erection of the scaffold.

20 For supporting the stringers and cross ties and securing said elements firmly in 120

place, clamps of the following construction are secured to each standard or upright: Each clamp comprises a pair of half collars 35 provided at their opposite ends with ears 36 and 37, the ears 37 being spaced more widely apart than the ears 36 and forming one of the underlying supports or rests for a stringer or cross tie, each set of ears being connected together by a pair of bolts 38 and 10 a pair of nuts 39. Pivoted on the uppermost pair of bolts connecting ears 37, is an eye-bolt 40 and fitting at opposite sides of said eye-bolt are two short bars 41 constituting a lever pivoted at its lower end on the under- 15 most of the bolts 38 connecting ears 37, it being noted that the lower ends of the bars 41 curve inwardly so that the upper or straight portions of the bars may project vertically upward beyond the outer ends of 20 the ears 37 and the outer side of the stringer or cross tie resting on said ears, and secured to the said lever between the upper ends of the members 41 thereof, is a prong 42 to clamp the stringer or cross tie firmly against 25 the adjacent standard, the prong being adapted for embedment in the stringer or tie to guard against longitudinal movement or slippage thereof.

To apply the force on said lever necessary to clamp the stringer or cross tie in place and embed the prong therein as explained, the pivot bolt 40 extends outward between the bars or members of said lever and is engaged by a washer 43 and a clamp- 30 ing nut 44, the screwing home of the nut on the bolt causing the washer which bears against the outer edges of the members 41, to apply inward pressure thereon for the purpose explained. It will be understood 35 that the collar members of the clamps last above described, are of such construction that they can be fitted upon the standards at any point thereon, that is upon any member 12 thereof, thus avoiding the necessity 40 of making such collars of different sizes to fit different diameters.

If desired the scaffold may be so constructed that the cross ties shall rest directly on the stringers. In this event the collars 50 of the two clamps for securing the stringer and cross tie in position will be arranged in superposed relation below the stringer, the lever of the clamp for the cross tie extending upward sufficiently to engage said 55 cross tie and the lever of the other clamp extending upward past the first-named clamp and engaging the stringer. The constructions of the clamp in both cases will be identical except as regards the length of the 60 lever element. The construction shown, however, is the preferred construction as it gives greater leverage for clamping the stringer or cross tie in place and of course incidentally possesses greater strength.

65 The tie or anchor for connecting the

scaffold with the wall of a building, preferably consists of a pair of bars 45, spaced slightly apart and provided with oppositely bowed collar portions 46 to be clamped upon the adjacent standard or upright 3 by bolts 70 47 and nuts 48, the bars extending through the window opening and preferably resting on the wall and provided with a longitudinal series of openings 49. A pair of shoes 50 joined together at the lower edges rest on 75 the bars 45 and are provided with depending perforated portions 51 fitting between said bars, the parts 50 and 51 constituting a Y-shaped member in vertical section. Bolts 52 extend through said perforations of the 80 bars and depending portions 51, and nuts 53 engage the bolts, to secure the shoes firmly and rigidly to the bars. The bolts and nuts also secure against the outer sides of 85 said bars and shoes, levers 9, consisting of two-part members and pivoted to the upper ends of said levers at 55 are bolts 56 which extend through the upper portions 90 of their respective shoes and are engaged by clamping nuts 57 and washers 58, the screwing home of the nuts causing the washers to bear against edges of the shoes and thus cause the lower ends of the levers to 95 clamp firmly the wall, as shown clearly in Figure 6.

In the construction shown by Figures 10 and 11 for bracing the scaffold within a building, collars comprising two-part flanged members 59 are fitted upon the standards, and extending through the flanged ends or 100 ears of the collar members are brace rods 10, having eyes 60, the eye of each rod being pivoted on a bolt 61 which extends through a pair of angle plates 62 and is engaged 105 by a retaining nut 63. The angle plates 110 are rigidly secured to a shoe 11 of the type hereinbefore referred to, this shoe through the proper manipulation of nuts 64 and 65 being brought to bear firmly against the 115 wall of the building. After this adjustment is effected, the nuts 65 are turned to effect greater clamping action of the collar members 59 on the standards so that there shall be no chance of the anchor or brace sliding downward.

In Figure 1, it will be seen that a pair of adjacent standards or uprights are connected by cross rods 66 retained in place by nuts 67, these cross rods and said standards constituting a ladder whereby the 120 workmen can ascend or descend the scaffold.

From the above description it will be apparent that we have produced a knock down scaffold embodying the features of 125 advantage enumerated as desirable in the statement of the object of the invention, and while we have illustrated and described the preferred embodiments of the invention, it is to be understood that we reserve the right 130

to make all changes properly falling within the spirit and scope of the appended claims.

We claim:

1. The combination of a collar, a lever thereon provided with prongs, a bolt pivoted to the collar, and a nut engaging the bolt and lever to effect operation of the latter in the direction in which the prongs thereof project.
2. The combination with a standard, of a bar projecting laterally therefrom, a shoe secured to the bar, clamp levers on the bar, and means for causing the levers to approach for cooperative clamping action on an interposed object.
3. In a knock-down scaffold a base provided with an external groove and upwardly-opening socket, a standard fitting in said socket and resting upon said base and provided with an externally reduced portion above the base, and a clamp consisting of two parts secured together and upon the base, and lower part of the standard, the upper

halves of said parts fitting snugly in the reduced portion of the standard and the lower halves of said parts having ribs fitting snugly in the groove of said base.

4. In a knock-down scaffold, superposed standards fitting telescopically together, the lower one supporting the upper one, and provided, near its upper end, with a diametrically reduced portion, the upper standard at a point above the lower standard also having a diametrically reduced portion, and a clamp for securing the two standards together, said clamp comprising two members receiving the upper end of the lower standard and the lower end of the upper standard between them and snugly engaging the reduced portions of said standards, and means for drawing and holding said members firmly against the standards.

In witness whereof we hereunto affix our signatures.

FOKKO H. G. BRANDT.
GEORGE K. KRELL.
